CLAIM

The ornamental design for a housing of damper mechanism for ink jet printer, as shown and described.

DESCRIPTION

FIG. 1 is a top and left front perspective view of a housing of damper mechanism for ink jet printer, showing my design;

FIG. 2 is a front elevational view thereof;

FIG. 3 is a rear elevational view thereof;

FIG. 4 is a left side view thereof;

FIG. 5 is a right side view thereof;

FIG. 6 is a top view thereof; and,

FIG. 7 is a bottom view thereof.

Portions of the disclosure shown in broken lines form no part of the claimed design.
